UNITED STATES PATENT OFFICE.

JACOB JARVIK, OF NEW YORK, N. Y.

LAMBREQUIN.

1,272,959.

Specification of Letters Patent. Patented July 16, 1918.

Application filed October 11, 1917. Serial No. 196,085.

To all whom it may concern:

Be it known that I, JACOB JARVIK, a citizen of the United States, and a resident of the city of New York, borough of the Bronx, in the county of Bronx and State of New York, have invented a new and Improved Lambrequin, of which the following is a full, clear, and exact description.

Among the principal objects which the present invention has in view are: To furnish a simple, efficient and easy method for decorating a window or other opening; to regulate the lateral extension of the members of the extensible lambrequin; and to conceal the connections or lines of junction.

Drawings.

Figure 1 is a front view of a lambrequin constructed and arranged in accordance with the present invention, the lambrequin being shown as contracted;

Fig. 2 is a front view of the lambrequin, the same being shown as fully extended;

Fig. 3 is a rear view of the lambrequin constructed as shown in Fig. 1, a portion of the covering of the rear lining being removed to show the equalizing mechanism for controlling the expansion of the lambrequin;

Fig. 4 is a vertical cross section, the section being taken as on the line 4—4 in Fig. 3;

Fig. 5 is a rear view of the lambrequin as shown in Fig. 2, the back covering being removed to show the equalizing mechanism in fully expanded position;

Fig. 6 is a horizontal section of the lambrequin shown in Fig. 5, the section being taken as on the line 6—6 in Fig. 5.

Description.

As seen in the drawings, lambrequins when constructed in accordance with the present invention provide three main sections, being central section 11 and end sections 12. The end sections 12, as shown best in Fig. 6 of the drawings, have each a cheek piece 13 for boxing the ends of the lambrequin or for filling in the space between the standing structure to which the lambrequin is applied and the base of the lambrequin or the sections 12 thereof. As shown best in Figs. 1 and 2 of the drawings, the sections 11 and 12 have shaped lower edges ornamenteally arranged to form with

one another a continuous design, the lines whereof are best suited for a heading or top ornament for a window or door opening.

The sections are preferably constructed as panels, employing for this purpose, wood or other suitable material, such as binder's board. Suitably mounted on the wood panels 14 and 15 forming the backs of the sections 11 and 12, respectively, are grooved rails 16 and 17, as best shown in Fig. 4. The rails 16 and 17 are disposed in paired relation and are provided to co-operate with rails 18 at the upper edges of filler sections 19. The sections 19 are provided with a relatively straight lower edge having an ornament 20 corresponding with the ornament 21 with which the sections 11 and 12 are furnished, as shown best in Fig. 2 of the drawings. To conceal the joints between the sections 11, 12 and 19, the vertical edges of the sections 11 and 12 are ornamented with folds 22 or other suitable devices, which will overlie the edge of the panels 11 and 12 and the adjacent portions 80 of the sections 19.

When arranged as above described, it will be seen that as the sections 11 and 12 are separated, the sections 19 are exposed and fill the intervening spaces between the said sections 11 and 12. It will also be noted that the ornaments 22 covering as described the joints between the sections 11 and 12, carry out the illusion of a continuous structure.

It is obvious that the sections 12 at both sides of the section 11 should be separated therefrom at equal distances, and that the extended structure should not sag when outstretched. To this end, it will be noted that the rails 18 have dove-tailed tongues 23, which fit corresponding grooves in the rails 16 and 17.

The union thus formed between the said rails 16, 17 and 18 resists any sagging or parting tendency of the said rails in vertical directions. The noted bending tendency is further resisted by the lazy-tong-connecting structure at the back of the panels, and which is secured thereto and to the reinforcing braces 24 and 25 on the sections 11 and 12, respectively, by means of the pivot pins 26 and 27. The lazy-tong structure is further reinforced intermediate the pivot pins 28 by the collapsing levers 29 and rocking arms 30. The levers 29 and arms 30 co-operate to retract the pins 28 from the posi-

tion shown in Fig. 5 of the drawings, to the position shown in Fig. 3 of the drawings. In the movement of the arms 30, it will be noted that they rotate on the pins 26 through 5 an arc of approximately ninety degrees, retracting in this manner the levers 29 and pins 28 inwardly toward the pins 26.

The operation of the lazy-tongs having the links 31 and 32 and the cross connecting 10 arms 33 is amplified over the conventional movement of such a structure, by the operation of the levers 29 and arms 30, so that the arms 33 of the lazy-tongs have the same scope of movement as the arms 30. This 15 action retracts the links 31 and 32 beyond their inner connections as shown best in Fig. 3, with the result that an amplified movement is obtained for the collapsible regulating structure,

20 With a connection such as above described, it will be recognized that the lambrequin may be expanded or contracted to any desired degree without sagging of the sections forming the said lambrequin.

25 As best shown in Figs. 3 and 4, cover plates 34 and 35 are attached to the rails 16 and 18, respectively. The meeting edges of the said plates overlie one another. These 30 plates serve to close or conceal the lazy-tongs and lever-supporting connecting structure provided for the sections 11, 12 and 19.

Between the cheek pieces 13, extends a

collapsible curtain rod. The curtain rod is formed of telescopic tubular sections 36 and 37.

35 A lambrequin constructed as above described is usually installed in service by hanging the same on hooks provided in a standing structure. To engage the hooks so provided, the lambrequin has bracket plates 40 38. The plates 38 are suitably attached to the cheek pieces 13, as seen best in Fig. 4 of the drawings.

Claim.

45 A lambrequin comprising a plurality of slidably connected rigid supporting sections; a plurality of cross arms pivotally connected in paired relation and mounted, one pair on each of said supporting sections; a plurality 50 of links pivotally connecting the ends of each of said arms and the adjacent supporting section for moving said adjacent section in conformity with the swing of said arms, the length of said links being unrelated to 55 the length of said arms; and a plurality of cover plates, each mounted at the rear of one of said supporting sections for forming in connection therewith box-like recesses for 60 said cross arms and links, said cover plates being arranged to slide each upon the other for forming box-like members telescopically related.

JACOB JARVIK.
